**MEANS AND TECHNIQUES FOR SILENCING
SOLENOID-OPERATED DEVICES**

William A. Ray, North Hollywood, and Laurence C. Biggle, Altadena, Calif., assignors to International Telephone and Telegraph Corporation, Baltimore, Md., a corporation of Maryland

Filed July 17, 1961, Ser. No. 124,528
8 Claims. (Cl. 317—185)

The present invention relates to means and techniques for silencing solenoid-operated devices, particularly relays, gas valves and the like.

Briefly, the present invention is concerned with the reduction or substantial elimination of so-called "clicking" noises when the solenoid armature or plunger is moved into engagement with a pole piece or stop upon energizing of the solenoid. The same means are also instrumental in reducing other noises which would otherwise be transferred to the outer housing, usually the so-called cover member of the device. In the particular forms of the invention disclosed herein there is some sound-absorbing or deadening material interposed between the solenoid magnetic structure and its cover member so as to minimize or substantially eliminate the transfer of acoustical energy from such magnetic structure to the cover member by either attenuating such acoustical energy or preventing the transfer of such energy from the magnetic structure to the cover member. Using such means, the so-called sounding board effect of the cover member is reduced or substantially eliminated.

It is therefore a general object of the present invention to provide constructions which function to produce the desired results indicated above.

A specific object of the present invention is to provide a construction of this character wherein both the magnetic structure and its cooperating armature are both resiliently supported and particularly so when the same is incorporated in a solenoid-operated gas valve as disclosed herein.

Another specific object of the present invention is to provide constructions of this character involving the use of a massive member between the magnetic structure and the cover, such member and cover being resiliently supported with respect to each other so that the full effect of the massive member may be realized to absorb such clicking noises which are considered essentially to be comprised of a series of high frequency oscillations.

Another specific object of the present invention is to provide constructions of this character involving the use of packing material between the solenoid and its cover.

The features of the present invention which are believed to be novel are set forth with particularity in the appended claims. This invention itself, both as to its organization and manner of operation, together with further objects and advantages thereof, may be best understood by reference to the following description taken in connection with the accompanying drawings in which:

FIGURE 1 is generally a sectional view through a solenoid-operated gas valve taken substantially along the line 1—1 in FIGURE 2.

FIGURE 2 is a sectional view taken generally along the line 2—2 in FIGURE 1.

FIGURE 3 is a perspective view illustrating details of the bracket incorporated in the valve shown in FIGURES 1 and 2.

2

FIGURE 4 is generally a sectional view taken along the line 4—4 in FIGURE 2.

FIGURE 5 is a perspective view illustrating one of the resilient washers interposed between the bracket shown in FIGURE 3 and the magnetic structure of the valve shown in FIGURE 1.

FIGURE 6 is generally a sectional view taken along the line 6—6 in FIGURE 2.

FIGURE 7 is a view partly in section and partly in elevation of a modified form of construction also embodying features of the present invention.

FIGURES 8 and 9 are also combined sectional and elevational views of other gas valves embodying features of the present invention.

FIGURES 10 and 11 illustrate another form of the invention, FIGURE 10 being generally a longitudinal sectional view and FIGURE 11 being a perspective view showing one of the elements illustrated in FIGURE 10.

Referring to the form of the invention illustrated in FIGURES 1—6 both inclusive, the solenoid-operated gas valve includes a conventional valve body 10 having inlet and outlet openings (not shown) between which is an angled partition 12 which defines a circular valve seat 14 at its upper end.

The movable valve member 15 which cooperates with the seat 14 is in the form of a disc of gasket material which is carried on the flexible diaphragm member 16 together with the armature disc 17 on the opposite side of the diaphragm, and an apertured metal disc 18 sandwiched between the valve member 15 and diaphragm 16, these parts being maintained in their sandwiched relationship shown by rivet 20 which passes in turn through washer 21, valve member 15, disc 18, diaphragm 16 and is affixed to the armature disc or plate 17.

The peripheral edge of the diaphragm 16 is clamped between the valve body 10 and the cover member 24 which is preferably a heavy walled massive body of, for example, cast iron. Preferably this cover member 24 is resiliently supported on the valve body 10 using a resilient fastening connection between the cover 24 and valve body 10 as exemplified in FIGURE 4 but in other cases the cover 24 may be bolted directly to the valve body 10 without any resilient means interposed therebetween.

This cover member 24 resiliently supports the bracket member 26 using the construction shown in FIGURE 4; and in turn, the bracket 26 has secured thereto the magnetizable structure which comprises the stack of flat, generally E-shaped laminations 30 and coil 32. Each of these laminations comprises two outer legs 34 and 36 which are engageable by the attracted armature 17 and the center leg 38 which projects partially into the confines of the coil 32. The coil 32 is secured to the stack of laminations 30 using conventional means as, for example, spring elements (not shown) acting between the stack of laminations 30 and the coil form on which the coil 32 is mounted.

The stack of laminations 30 is secured to the downwardly extending legs of bracket 26 by bolts or rivets 40 passing through aligned apertured portions of the same. The upper portion of bracket 26 is secured to the cover 24 by the two bolts 42 which are threaded into enlarged bosses in the cover member 24 as shown in FIGURE 4 with vibration-absorbing washers 44 interposed between the bracket 26 and cover member 24. These sound-ab-

sorbing or resilient means 44 may take other forms and shapes and may be of the conventional types used in shock-mounting equipment; and in general, it is understood that such means 44 comprises a means for absorbing shock forces or other vibrational forces or other movement of the magnetizable structure so that the cover member 24 is rendered relatively insensitive thereto.

This bracket member 26 may also have integrally formed therewith a third leg 26A on which is affixed as, for example, by gluing a felt filter pad 50 serving as a filter element for the flow of gas from the inlet side of the valve and through the gas channel 24A in a portion of the cover member 24. This is for the purpose of subjecting both sides of the diaphragm 16 to the same gas pressure so that, in general, operation of the solenoid is not affected by gas pressure.

The cover 24 also carries a pair of insulated electrical terminals 52 which sealingly extend through the upper wall of the cover 24 and which are connected to opposite terminals of coil 32 for energizing the same.

In operation of the device shown in FIGURES 1-6, energization of the coil 32 results in movement of the armature plate or disc 17 into engagement with the legs 34 and 36 of the magnetizable structure against the action of the diaphragm 16 as well as against the action of the prestressed coil compression spring 54 which has one end thereof recessed in the plate 17 and the other one of its ends bearing against the center magnetizable leg 38. It is noted that a cylindrical projection 54A suitably fastened as, for example, by riveting to the stack of laminations 30 extends partially within the confines of the spring 54 to retain the same in center position.

When the armature plate 17 contacts the pole pieces 34, 36, noise is developed and it is considered that such noise, while it may sound in the nature of a "clock," actually predominates in a series of high frequency oscillations. Be that as it may, the shock and noise produced thereby is absorbed or attenuated largely in the shock-absorbing or sound-attenuating means 44 so that the sound which otherwise would be transferred to the cover 24 is prevented from reaching cover 24. It will also be noted that the diaphragm member 16 which connects the armature 17 to the cover 24, being resilient, prevents or attenuates the passage of acoustical energy along that particular path. Another contributing factor is the massiveness of the cover member 24 which may or may not be resiliently supported on the valve body 10 and the cover 24, because of its massiveness, contributes also to the attenuation of high frequency vibrations which may be transferred thereto.

The modified arrangements shown in FIGURES 7, 8 and 9 involve the use of a sound-deadening or absorbing material interposed between the cover and the magnetic structure, such material being in the form of steel wool, aluminum mesh or any other similar metallic fibrous materials. A metallic fibrous material is preferred since it will act as a means for conducting heat away from the coil to the cover but in such case it is preferred that intermediate portions of the fiber be coated with some sound-deadening material such as that used in so-called undercoating of automobiles. In those instances where the transfer of heat from the coil to the surroundings is not a problem, the fibrous material may be non-metallic such as a loose mass of felt fibers.

Certain constructional features of the solenoid-operated gas valves shown in FIGURES 7 and 8 are also described in the copending application of William A. Ray, one of the applicants herein, Serial No. 670,606, now U.S. Patent 2,998,552, patented August 29, 1961. The magnetic structures in the valves shown in FIGURES 7 and 8 herein are the same and correspond to the disclosure of the magnetic structure in said pending application Serial No. 670,606.

In FIGURES 7 and 8 the plunger 102 is secured to the diaphragm 103 by a riveted extension 104 thereof with

the washer 105, valve member 106, diaphragm 103 and magnetizable plate 107 sandwiched between the riveted head 104 and armature 102 in that order. The movable valve member 106 cooperates with the raised valve seat 108 of the valve body 109 having an inlet 110, and outlet 111. The valve member 106 is normally pressed against the valve seat 108 by the combined action of the diaphragm 103 and the spring member 112 acting between the plate 107 and the stepped, flanged member 114. The peripheral edge of the diaphragm 103 together with a gasket member 115 is clamped between the valve body 109 and a flanged portion of the member 114. The diaphragm 103 is held in this clamped condition by bolts (not shown) passing through the member 114 and threaded into the valve body 109. A tube 117 has its lower end affixed as, for example, by welding or brazing to this member 114 and has its upper end flared at 117A for fastening purposes. A pole piece 120 extends into the confines of coil 121 and is fastened to the flared tube 117A by machine screw 122 which passes through aligned apertured portions of a lock washer 124 and a magnetizable plate 125 and is threaded into the pole piece 120 so as to draw the same up against the flared portion 117A to secure this particular structure. It is noted that a generally annular cover member 127 is also retained by the machine screw 122 and has its lower peripheral edge bearing on an annular phenolic hard rubber ring 128 which is seated on a stepped portion of the member 114. This cover member 127 thus encloses the coil 121 which has its coil form bearing against the interior of the cover member 127 at its upper end and the lower end of the coil form engages the member 114 through a resilient washer 130 to support the coil form in position.

This inner cover member 127 has an apertured portion 127A through which the coil leads 121A and 121B pass.

In accordance with an important feature of the present invention there is provided an outer cover member 140 (FIGURE 7) and cover member 142 (FIGURE 8) which overlie the inner cover member 127 to provide a relatively large space therebetween which is filled with some sound-absorbing or attenuating material of the character previously described to prevent or substantially eliminate the transfer of sound from the inner magnetic structure to the outer cover member 140 or 142.

In FIGURE 7 this outer cover member 140 may be of sheet metal having an out-turned lower edge which bears on the phenolic hard rubber ring 128; and is also provided with an apertured portion receiving grommet 145 through which the coil leads 121A, 121B pass. The material 147 of fibrous nature between the inner and outer cover members 127 and 140 is of the character previously described.

In FIGURE 8 the outer cover member 142 is a massive body of, for example, thick-walled cast iron and is provided with an internally threaded boss 142A to receive a pipe conduit fitting. The lower peripheral edge of the cover 142 encircles the phenolic hard rubber ring 128 and may be secured thereto by small screws, the same being true of the cover 140 in FIGURE 7 which may likewise be secured to the corresponding ring 128 by small screws.

In operation of the devices shown in FIGURES 7 and 8, energization of the coil 121 results in the armature or plunger 102 contacting its pole piece 120 in which case there would be an objectionable "click" noise if the outer cover member 140 or 142, as the case may be, the fibrous material 147 and sound-dampening ring 128 were not provided. It is preferred that the outer cover be of massive thick-wall construction as shown in FIGURE 8 since the same contributes to attenuating high frequency noises which may possibly pass through the sound-deadening material 147.

In the arrangement shown in FIGURE 9 the magnetic structure is essentially the same as that described in con-

nection with FIGURES 7 and 8 but in this case the tube 217 (corresponding to the tube 117 in FIGURE 8) is affixed to an intermediate portion of the pole piece 120 and a more massive thick-wall inner cover member 227 (corresponding to the inner cover member 127 in FIGURES 7 and 8) is secured to the pole piece 120 by fastening screw 122. The coil 121 with its coil form is again resiliently mounted between the lower member 114 and the inner cover 227. In this case the lower annular flanged portion of cover 227 bears against sound-absorbing material 228 in the nature of a tightly-packed aluminum mesh which may have the strands thereof coated with some insulating sound-deadening material such as that used in the undercoating of automobiles. Also in this case the outer cover member 240, corresponding to the cover member 140 in FIGURE 7, encircles the sound-deadening material 228 and may be spaced from the adjacent stepped flange member 114 or may be secured thereto by small screws (not shown). Any of the materials mentioned above of fibrous nature may be interposed between the inner cover member 227 and the outer cover member 240 and preferably in FIGURE 9 this material is a medium-packed aluminum mesh coated with some sound-deadening material.

In comparing the arrangements shown in FIGURES 8 and 9, it will be observed that one notable distinction is that whereas in FIGURE 8 the massive cover 142 is the outer cover, in FIGURE 9 the massive cover 227 is the inner cover member. In other words, the inner and outer cover members are essentially interposed.

In the construction shown in FIGURES 10 and 11 there is disclosed a valve body 300 having an inlet and outlet port as described above in connection with the previous figures and in such valve body 300 is the valve seat 301 engageable with the movable closure member 302 which is mounted on the flexible diaphragm 303 which has its marginal edge sandwiched and clamped between the valve body 300 and the valve cover member 304, such clamping being accomplished by the bolts 305 passing through the cover member 304 and threaded into the valve body 300.

More specifically, the closure member 302, which is in the form of an annular disc, is mounted on the diaphragm 303 by providing the armature 307 with a stud 307A which passes through apertured portions of the diaphragm 303 and closure member 302 and washer 308 and which then has its end upset as, for example, to provide a rivet-type connection.

This armature 307 cooperates magnetically with the centrally located pole piece 310, which is in the form of a rod, and also with the magnetizable core member 311 which, as illustrated in FIGURE 11, is generally cup-shaped with two side walls removed therefrom to define a base portion 312 and two side wall portions 313 and 314, the base portion 312 being apertured to allow passage of the fastening screw 315 which is threaded into the central magnetizable pole piece 310. This assembly may be locked by incorporating the lock washer 316 between the head of screw 315 and the base portion 312. The solenoid coil 317 wound on spool 318 surrounds the pole piece 310 and is generally snugly fitted within the core member 311, such spool 318 having ears 319 integrally formed thereon to fit between the side wall portions 313 and 314 of the core member 311 so that the same is prevented from turning.

A spacer washer 320 of resilient material is interposed between the base portion of the core member 311 and the cover member 304 to absorb or attenuate shock or impact forces occurring during operation of the solenoid valve.

An epoxy resin 321 is molded within the space between the core member 311 and adjacent side walls of the cover member 304 also for sound-deadening purposes and for supporting a shading ring structure 322 which is generally cup-shaped having that end which is embedded in the epoxy 321 bent as shown to better secure the shading ring

5 structure 322 in the epoxy. The base portion of the shading ring structure 322 is circularly apertured to allow the central pole piece 310 to extend therethrough and is also provided with a plurality of spaced and radially extending slits 322A. This shading ring structure 322 also engages a portion of the coil form 318 to maintain the coil form and, of course, the coil 317 in place. A coil compression spring 323 has one of its ends bearing against the shading coil structure 322 and the other one of its ends bearing against the armature 307 to normally maintain the valve 301, 302 in its closed position as illustrated.

10 The leads of coil 317 are connected as, for example, by soldering, to bolts 324, 325. These electrical connecting bolts 324 and 325 serve to secure the terminal board 326 on the cover member 304 as well as to fasten the terminals or binding posts 327 and 328. It will be seen that these bolts 324 and 325 have their lower ends seated against a generally annular ring-shaped member 329 of insulating material which is formed to project partially up into the apertured portions 304A and 304B of the cover member 304. Sound-deadening or absorbing washers 330 and 331 are interposed between the terminal board 326 and the insulating member 329.

15 Using this construction shown in FIGURES 10 and 11, it will be seen that this construction also incorporates sound-deadening or attenuating material which minimizes greatly the transmission of those high frequency components previously mentioned from the magnetizable element to the cover member 304, this being accomplished by incorporation of the sound-deadening washer 329 between the core member 311 and the cover and the epoxy resin 321 which is interposed between the cover and the core structure and which prevents substantial noises from being transmitted through the shading coil structure 322 to the cover member.

20 25 30 35 While the particular embodiments of the present invention have been shown and described, it will be obvious to those skilled in the art that changes and modifications may be made without departing from this invention in its broader aspects and, therefore, the aim in the appended claims is to cover all such changes and modifications as fall within the true spirit and scope of this invention.

We claim:

1. A sound-deadened solenoid comprising a magnetic structure; an armature attracted by said structure; stop means engaged by said armature when said magnetic structure is energized and producing noise upon engagement between the armature and stop means; a cover member surrounding said structure; and sound-deadening material interposed between said stop means and said cover member and substantially preventing the transfer of said noise from said stop means to said cover, said cover member comprising an outer cover member; a second inner cover member inside of said outer cover member; said inner cover member also surrounding said magnetic structure and said stop means; and said sound-absorbing material being disposed between said inner and outer cover members.

2. A solenoid as set forth in claim 1 in which said inner cover member comprises the more massive thick-walled cover member.

3. A solenoid as set forth in claim 1 in which said outer cover member comprises the more massive thick-walled cover member.

4. A solenoid as set forth in claim 1 in which said sound-absorbing material comprises fibrous material.

5. A solenoid as set forth in claim 4 in which said fibrous material is metallic for heat transfer to the outer cover member.

6. A solenoid as set forth in claim 5 in which said metal fibers are coated with a sound-deadening material.

7. A sound-deadened solenoid comprising a magnetic structure; an armature attracted by said structure; said magnetic structure incorporating a pole piece engaged by said armature; a cover member surrounding said magnetic

structure; sound-deadening material interposed between said pole piece and said cover member; a shading ring structure surrounding said pile piece; sound-deadening material between said magnetic structure and said cover member; said shading ring structure being secured in the last-mentioned sound-deadening material.

8. A solenoid construction as set forth in claim 7 in which a slotted cup-shaped core member partially surrounds said magnetic structure and is engageable with said armature, and the last-mentioned sound-deadening material is interposed between said cup-shaped core member and said cover member.
